ROBERT V. PROCTOR, OF YOUNGSTOWN, OHIO, ASSIGNOR TO THE COMMERCIAL SHEARING & STAMPING COMPANY, OF YOUNGSTOWN, OHIO, A CORPORATION OF OHIO.

DRYING RACK.

Application filed November 10, 1926. Serial No. 147,536.

This invention relates to drying racks, and particularly to a rack for holding pallets on which ceramic ware is placed in the "green state" and kiln dried. 55

When ceramic ware is molded, it is placed on pallets which are preferably made of light metal and these pallets are stacked so as to utilize space in the most efficient manner. Some pallets are arranged to stack one 10 upon the other, but in many cases it is impossible to do this, and racks are employed for holding the pallets one above the other in spaced relationship.

The green ware is very easily broken, and it is therefore important that the pallets be uniformly supported and not subjected to twist.

The drying racks heretofore constructed have been open to the objection that if they are placed upon an irregular floor or if, due to inaccuracies in construction, they are not engaged by the lift truck in the exact manner intended, the racks themselves have become twisted. This twisting has been in turn transferred to the pallets with a consequent breakage of the ware.

I have found that this difficulty may be overcome by providing a drying rack having a pair of upstanding legs with pallet holding means on the legs, and a hollow girder rigidly connected to the legs and spacing the same apart. This girder is conveniently made of two channels placed face to face and welded together along the edges. Preferably the hollow girders are spaced a distance above the floor and are adapted for engagement by a lift truck. In some cases, it may be desirable to provide a diagonal brace in a generally horizontal plane.

40 In many cases it is desirable to utilize longitudinal as well as transverse hollow girders. The longitudinal girders are to prevent twisting when the rack runs over on an uneven floor. The longitudinal girders are 45 not necessarily in the same plane as the transverse girders, but they should be rigidly attached.

It is very desirable to weld all of the parts together in a rack of this character. The parts are necessarily made of relatively light gage metal and if rivets are employed there is not sufficient resistance in the metal surrounding the rivet to hold under heavy loads. As a result, the rivet holes become enlarged

and the entire rack loosens up. I preferably weld all of the parts together as this is found in actual practise to produce a rack which will stand up over periods of time without becoming loose.

In the accompanying drawings which 60 illustrate a preferred embodiment of the invention,

Figure 1 is a perspective view of a drying rack showing several pallets in place;

Figure 2 is a horizontal section through 65 a modified form of rack, said section being taken in a plane above the hollow girders;

Figure 3 is a partial section taken on the line III-III of Figure 2;

Figure 4 is a view corresponding to a portion of Figure 2, but showing a modified form of upstanding legs;

Figure 5 is a side elevation of a wall rack employing hollow longitudinal girders;

Figure 6 is a section taken on the line 75 VI-VI of Figure 5;

Figure 7 is a detail view showing a part of the construction of the rack illustrated in Figures 5 and 6;

Figure 8 is a section taken on the line 80 VIII-VIII of Figure 6; and

Figure 9 is a section taken on the line IX-IX of Figure 8.

Referring first to Figure 1, there is shown a drying rack comprising four upstanding 85 legs 2 arranged in opposed pairs. The legs are channel shaped, and each pair is placed with the backs of the channels opposing one another.

The pairs of legs are connected by hollow 90 girders 3 which are made of two channels placed face to face and welded along the edges, as indicated at 4 in Figure 2. It will be understood that the rack shown in Figures 2 and 3 differs from that in Figure 1 95 only in the inclusion of a diagonal brace, hereinafter described. The hollow girders are connected to the upstanding legs by gusset plates 5 which provide a rigid connection. Each leg is provided with a foot 6 to give 100 ample bearing surface.

Each pair of legs with its connecting hollow girder forms a generally U shaped frame having downwardly extending legs. The space below the girder 3 is provided for the 105 reception of a lift truck of any desired type. These trucks have supporting faces which are adapted for vertical movement so as to

elevate from the ground racks or similar structures under which they are placed.

The U-shaped frames are connected by channels 7 securely fastened to the upstanding legs 2, as by spot welding. Flanges 8 of the channels provide bearing supports for pallets 9. The ends of the flanges 8 are chamfered off as indicated at 10 so as to eliminate sharp corners.

- 10 The above described rack has been found to be very desirable in practice and capable of maintaining its original shape without twisting, even though it is irregularly supported. As an additional precaution against twisting, it may be desirable to provide a diagonal brace such as shown at 11 in Figure 2. This brace preferably lies in the general plane of girders 3 so as to provide an unobstructed pallet receiving space.
- 15 20 The brace comprises a pair of hollow girders arranged in the form of an X.

Figure 4 shows a portion of a drying rack very similar to that of Figure 1, except that the upstanding legs 2 instead of being channels, are made in the form of hollow tubes 12. These hollow tubes may be made in one piece by any desired manufacturing process, or they may be made by welding two channels together in the same way as the hollow girders 3 are made. Conversely, the hollow girders 3 may be made of a one-piece tube, if desired.

In Figures 5 to 9, inclusive, there is shown a wheeled rack. It comprises upstanding channels 20 carrying pallet receiving channels 21.

The channels 21 are similar to the channels 10 in Figures 1 and 2. They are welded to the upstanding legs 20.

The channels 20 at either rack are connected to cross members 22 and 23. The cross member 22 is channel-like in cross-section, while the cross member 23 is in the form of a structural Z. Gusset plates 24 are provided at the joints, and the top flanges of the members 22 and 23 are connected by a plate 25. All of the parts are welded together.

The two ends of the rack are connected by longitudinal girders 26 which are tubular in form, as shown in Figure 9. Gusset plates 27 are employed at each corner for connecting the tubular member 26 to the end framing of the rack. Welding is also employed for joining these parts.

The entire rack is mounted on casters 28.

Figure 8 most clearly shows the hollow cross girder in the embodiment of the invention shown in Figures 5 to 9, inclusive. This section is taken on the line VIII—VIII at the junction of two of the gusset plates 24, but the adjoining edges of such plates are welded together so that, in effect, they form a single piece of metal. Since the plate 25 extends all the way across the rack, the combination of the channel 22, Z 23 and plates 25

and 27 forms a hollow cross girder serving the same purpose as the hollow cross girder in the embodiment of Figures 1 to 4, inclusive. It will be noted from Figure 1 that the gusset plates 5 are shown as spot-welded. Experience shows that rivets are not sufficient to hold the parts rigidly over a continued period of time.

I have illustrated and described a preferred embodiment of the invention and certain modifications thereof, but it will be understood that the invention may be otherwise embodied within the scope of the following claims.

I claim:

1. A drying rack comprising upstanding legs, the legs at one side of the rack being unconnected at the top to the legs at the other side of the rack, pallet holding means on the legs, and a hollow girder rigidly connected to the legs and spacing the same apart, the hollow girder being remote from the top of the rack, and the joints being welded.

2. A drying rack for ceramic articles comprising a hollow girder, a pair of spaced legs rigidly and permanently secured to the girder and upstanding therefrom to form an open top frame, and pallet holding means on the legs.

3. A drying rack for ceramic articles comprising a hollow girder, a pair of spaced legs rigidly and permanently secured to the girder and upstanding therefrom to form an open top frame, and pallet holding means on the legs, the legs extending downwardly from the girder a sufficient distance to permit of placing a lift truck beneath the girder.

4. A drying rack for ceramic articles comprising hollow girders, a pair of spaced legs associated with each of said girders and rigidly and permanently secured thereto and upstanding therefrom to form a plurality of spaced open topped frames, and pallet holding means connected to the legs.

5. A drying rack comprising hollow girders, a pair of spaced legs associated with each of said girders and rigidly secured thereto and upstanding therefrom to form a plurality of spaced open topped frames, pallet holding means connected to the legs, and a diagonal brace lying in the general plane of the hollow girders.

6. A drying rack comprising hollow girders, a pair of spaced legs associated with each of said girders and rigidly and permanently secured thereto and upstanding therefrom to form a plurality of spaced open topped frames, and pallet holding means connected to the legs, the pallet holding means acting as the sole means for spacing the frames apart.

7. A drying rack for ceramic articles comprising a hollow girder, a pair of upstanding legs, each end of the girder abutting a side of one of said legs and being rigidly and per-

manently secured thereto so as to form an open top frame, and pallet holding means on the legs.

8. A drying rack for ceramic articles comprising a hollow girder, a pair of upstand legs, each end of the girder abutting a side of one of said legs, a gusset plate welded to a leg and to the girder so as to rigidly secure the same, and pallet holding means on the legs.

9. A drying rack comprising a pair of hollow girders, each having associated there-

with a pair of upstanding legs, each end of each girder abutting a side of one of said legs and being rigidly secured thereto so as to form a pair of rigid open topped frames, and pallet holding means extending from one frame to another and rigidly connected to the upstanding legs so as to space the frames apart.

In testimony whereof I have hereunto set my hand.

ROBERT V. PROCTOR.
